WELL TUBING CATCHER

Samuel Allen Guiberson, III, Dallas, Tex., assignor to The Guiberson Corporation, Dallas, Tex., a corporation of Delaware

Application July 8, 1935, Serial No. 30,291

8 Claims. (Cl. 103—219)

This invention relates to new and useful improvements in well tubing catchers.

One object of the invention is to provide an improved tubing catcher which is constructed so as to be readily assembled or dismantled for purposes of replacement of parts, or for any other reason.

An important object of the invention is to provide a tubing catcher having an improved link construction, whereby the usual weight may be readily attached to or detached from the movable gripping slips of the catcher, said construction being exceptionally cheap and simple in manufacture and providing a more rigid and stronger connection between the parts.

A further object of the invention is to provide an improved link for connecting the weight and gripping slips of a tubing catcher, said link comprising an elongated shank having right angular cross arms at each end, said arms being rotatably confined in slots in said slip and weight, whereby the link is pivotally connected to the parts and the load on the link is carried by the cross, which provides a stronger structure than the usual pivot pin which connects the link to the slip and weight.

A construction designed to carry out the invention will be hereinafter described, together with other features of the invention.

The invention will be more readily understood from a reading of the following specification and by reference to the accompanying drawings in which an example of the invention is shown, and wherein:

Figure 1 is a view, partly in elevation and partly in section of a tubing catcher having links constructed in accordance with the invention, incorporated therein,

Figure 2 is a view partly in elevation and partly in section, taken at right angles to Figure 1 and showing only the upper portion of the tubing catcher,

Figure 3 is a horizontal, cross-sectional view, taken on the line 3—3 of Figure 1,

Figure 4 is a horizontal cross-sectional view, taken on the line 4—4 of Figure 1,

Figure 4a is a transverse, sectional detail taken on the line A—A of Figure 3,

Figure 5 is a view partly in section and partly in elevation of the upper portion of a tubing catcher showing another form of the invention,

Figure 6 is a horizontal, cross-sectional view, taken on the line 6—6 of Figure 5, and

Figure 7 is a horizontal, cross-sectional view, taken on the line 7—7 of Figure 5.

In the drawings, the numeral 10 designates a

tubular mandrel which forms the main support of the tubing catcher. At the upper end of the mandrel, a slip head 11 is mounted. This head is formed with three inclined guide faces 12 which are spaced equally around the mandrel. The lower end of the head is provided with an annular outwardly extending collar 13 which is preferably made integral therewith.

Each guide face has a central dovetail rib 14 which extends through the vertical length of said face, and this rib engages a complementary dovetail groove in the rear side of a gripping slip 16, whereby the slip is slideable vertically on the face. It is pointed out that each face is inclined inwardly toward its lower end, whereby when the slip is at the lower end of said face, it is retracted from the inner wall of the casing A. When the slips are at the upper end of the inclined faces, the slips have moved outwardly laterally so that the gripping teeth of said slips are engaging the casing wall to prevent downward movement of the catcher. All of the above parts are of the usual construction and are, therefore, subject to variation.

A weight 17 is slidably mounted on the mandrel 10 below the annular collar 13 and is provided with a counterbore 18. The counterbore extends from the lower end of the weight and terminates near the upper end thereof, whereby an internal annular shoulder 19 is formed within the weight near the upper end thereof. A coiled spring 20 surrounds the mandrel and it is disposed within the counterbore, being confined between the shoulder 19 and a coupling collar 21 at the lower end of the mandrel. The collar is internally threaded, whereby the tubing B may be connected to the mandrel. The upper end of the head 11 is provided with an externally threaded nipple 11' so that the tubing B may be connected to the upper end of the tubing catcher. Thus, it will be seen that the device may be readily connected into the tubing.

The usual practice has been to connect the upper end of the weight 17 with the lower end of the slips 16 by links which are pivoted to said weight and slips on pivot pins. This necessitates forming ears on the members and since the operation of the slips is controlled by the inertia of the weight, it is obvious that the pivot pins must carry the load. It has been found that due to the fact the ears formed on the parts must be comparatively small, the size of the pivot pins is limited. Therefore, the pins constantly break and must be replaced. Further, cost of manufacture is comparatively high due to the fact the

ears for carrying the pivot pins must be made integral with the weight and slips. Also, the assembling and dismantling is rather cumbersome.

To overcome the above difficulties and to provide a more simple and stronger link construction, a link 22 is employed for connecting each slip to the weight. The link comprises an elongated shank 23 which has a cross arm 24 at its upper end and a similar cross arm 25 at its lower end. The arms are disposed at right angles to the vertical axis of the shank. The cross arms are preferably cylindrical, but the shank may be any shape.

The under side of each slip is formed with a longitudinal groove 26 extending throughout its length (Fig. 3). A transverse groove 27 which is located at the center of the slip is of the same depth as the groove 26 and crosses the same at substantially a right angle, as is clearly shown in Figure 3. The grooves are substantially the diameter and width of the cross arm 24 and shank 23 of each link.

In pivotally fastening the upper end of each link to its slip, the cross arm thereof is entered into the longitudinal groove 26 and is located so that the shank 23 is aligned with the transverse groove 27. After the cross arm 24 is positioned in this way, a pair of retaining bars 28 are inserted in the groove 26 beneath the cross arm 24 on each side of the shank 23. The bars are welded, or otherwise suitably secured in position and it is obvious that said bars will prevent downward displacement of the link. Since the shank 23 is disposed in alignment with the transverse groove 27, said shank may be swung in said groove, and thus, a pivotal connection between the upper end of the link and slip is had.

Each link extends downwardly from the bottom of its slip 16 through a slot 13 in the annular collar 13. For pivotally securing the lower cross arm 25 of the link to the weight 17, the upper end of said weight is provided with an annular recess or groove 29 which extends outwardly from the bore of said weight. This groove is located slightly below the upper end of the weight as clearly shown in Figure 1, whereby the top 30 of the weight covers the top of the groove.

This top 30 has a trio of radial slots 31 cut therein (Fig. 4), which are located in vertical alignment with the shank 23 of each link. The lower cross arm 25 of each link 22 is entered into the annular groove 29, the shank 23 entering the radial slot 31. A snap ring 32 is then inserted in the inner end of the groove to close said groove and prevent inner displacement of the cross arms 25 of said links. The springiness of the ring causes the same to snugly engage the mandrel 10 (Fig. 4), whereby said ring remains positioned at the inner end of the groove 29. It is obvious that the cross arm 25 is confined within the groove, while the shank 23 of each link, being located within the slot 31 may swing in the slot radially of the weight, thereby providing a pivotal connection between the lower end of the link and weight.

The tubing catcher operation is the same as the usual devices of this nature. So long as the catcher is moved slowly within the casing, the weight 17 holds the slips retracted. However, if a break occurs and there is a sudden drop, the inertia of the weight causes the same to remain momentarily stationary. The head being connected with the tubing B through the mandrel 10 falls therewith, moving the slips outwardly in a

radial direction into gripping engagement with the well casing A, to arrest further downward movement of the tubing. The cross arms of the links carry the entire load of both slips and weight and thus increased contact area is provided which strengthens the structure and increases the life of the tubing catcher.

In assembling the device, the lower cross arm 25 is inserted in the groove 29 and the ring 32 located before the weight is slid onto the mandrel. The weight is then positioned on the mandrel and the upper cross arm attached thereto. The dismantling may be readily accomplished by merely removing the welded bars 28.

In Figures 5 to 7, I have shown another form of the invention. In this form, the lower cross arm 25 is fastened to the weight 17 in the same way except that the snap ring 32 is eliminated. The upper cross arm 24 is inserted in an annular groove 40 cut in each slip near its lower end. The shank 23 enters a radial slot 41 whereby the shank may swing radially of the mandrel 10. By observing Figure 6, it will be seen that the connection thus made is similar to the fastening of the lower cross 25 to the weight. In this form the mandrel 10 prevents displacement of the lower cross arm of each link from its groove while the cylindrical face on which each slip rides prevents the displacement of the upper cross arm from the groove 40.

What I claim and desire to secure by Letters Patent is:

1. A tubing catcher including, a support, gripping slips mounted on the support and arranged to be expanded radially to grip the well casing, a weight slidably mounted on the support, and a link for connecting each slip with the weight and having cross arms at its upper and lower ends, the lower end of each slip having a groove for receiving the upper cross arm of the link and the upper end of the weight being provided with an annular groove for receiving the lower cross arm, whereby the slips are connected to said weight.

2. A tubing catcher including, a support, gripping slips mounted on the support and arranged to be expanded radially to grip the well casing, a weight slidably mounted on the support, a link for connecting each slip with the weight and having cross arms at its upper and lower ends, the bottom of each slip having a longitudinal groove therein and also having a central transverse groove, whereby the upper cross arm may be inserted in the longitudinal groove with the shank of the link in alignment with the transverse groove, and retaining bars secured in the longitudinal groove beneath the cross arm to prevent displacement thereof from the groove, said weight having an annular groove formed in its upper end for receiving the lower cross arm of the link and also having radial slots formed in its top through which the shank of the link extends.

3. A tubing catcher including, a support, gripping slips mounted on the support and arranged to be expanded radially to grip the well casing, a weight slidably mounted on the support, a link for connecting each slip with the weight and having cross arms at its upper and lower ends, the bottom of each slip having a longitudinal groove therein and also having a central transverse groove, whereby the upper cross arm may be inserted in the longitudinal groove with the shank of the link in alignment with the transverse groove, retaining bars secured in the longitudinal groove beneath the cross arm to prevent displacement thereof from the groove, said weight

having an annular groove formed in its upper end for receiving the lower cross arm of the link and also having radial slots formed in its top through which the shank of the link extends, and 5 a retaining ring in the inner end of the groove in the weight for preventing displacement of the lower cross arm therefrom.

4. A tubing catcher including, a support, gripping slips mounted on the support and arranged 10 to be expanded radially to grip the well casing, a weight slidably mounted on the support, a link for connecting each slip with the weight and having cross arms at its upper and lower ends, the bottom of each slip having a longitudinal 15 groove therein and also having a central transverse groove, whereby the upper cross arm may be inserted in the longitudinal groove with the shank of the link in alinement with the transverse groove, and retaining bars secured in the 20 longitudinal groove beneath the cross arm to prevent displacement thereof from the groove, said weight having an annular groove formed in its upper end for receiving the lower cross arm of the link and also having radial slots formed in 25 its top through which the shank of the link extends, said radial slots being in direct vertical alinement with the transverse grooves in the bottom of the slips, whereby the link is in a vertical plane when connecting the parts.

5. A tubing catcher including, a support, gripping slips mounted on the support and arranged 30 to be expanded radially to grip the well casing, a weight slidably mounted on the support, a link for connecting each slip with the weight and having cross arms at its upper and lower ends, the bottom of each slip having a longitudinal groove therein and also having a central transverse 35 groove, whereby the upper cross arm may be inserted in the longitudinal groove with the shank of the link in alinement with the transverse groove, retaining bars secured in the longitudinal groove beneath the cross arm to prevent displacement thereof from the groove, said weight having an annular groove formed in its upper 40 end for receiving the lower cross arm of the link and also having radial slots formed in its top through which the shank of the link extends, said radial slots being in direct vertical alinement with the transverse grooves in the bottom of the 45 slips, whereby the link is in a vertical plane when connecting the parts, and a resilient retaining

ring in the inner end of the groove in the weight for preventing displacement of the lower cross arm therefrom.

6. A tubing catcher including, a tubular mandrel, gripping slips slideable on the mandrel and 5 having their inner faces engaging the outer face of the mandrel and arranged to expand radially when slid, a weight slidably mounted on the mandrel below the slips, and a link for connecting each slip to the weight and comprising a shank 10 having laterally projecting cross arms at its upper and lower ends, said arms being arranged to be pivotally fastened to each slip and weight to make the connection.

7. A tubing catcher including, a tubular mandrel, gripping slips slideable on the mandrel and 15 having their inner faces engaging the outer face of the mandrel and arranged to expand radially when slid, a weight slidably mounted on the mandrel below the slips, and a link for connecting each slip to the weight and comprising a shank 20 having cross arms at its upper and lower ends, each slip having a longitudinal groove in its rear wall for receiving the upper cross arm and having a central radial slot communicating with said 25 groove through which the shank extends, whereby the cross arms cannot be displaced downwardly and the shank may undergo a lateral swinging movement in the radial slot, said weight having an annular groove near its upper end for 30 receiving the lower cross arm and also having a radial slot in its top through which the shank of the links extend, whereby the lower cross arms of each cannot be displaced upwardly and the shank thereof may undergo a lateral swinging 35 movement in its radial slot, the mandrel forming a closure for the annular grooves in the slips and weight to prevent inward displacement of the cross arms.

8. As a sub-combination in a tubing catcher, 40 slips, a weight below said slips, a link for connecting the slips with the weight including an elongated shank, integral cross arms circular in cross-section at the ends of the shank extending laterally therefrom, said arms being disposed at 45 substantially a right angle to the longitudinal axis of the shank and projecting into grooves in the slips and weight respectively and means to retain said cross arms in said grooves.

SAMUEL ALLEN GUIBERSON, III.
